US0D1113470S

(12) **United States Design Patent** (10) **Patent No.:** **US D1,113,470 S**
(45) **Date of Patent:** **** Feb. 17, 2026**

(54) **SENSOR**

(71) Applicant: **KOITO MANUFACTURING CO., LTD.**, Tokyo (JP)

(72) Inventor: **Tomoya Higo**, Shizuoka (JP)

(73) Assignee: **KOITO MANUFACTURING CO., LTD.**, Tokyo (JP)

(**) Term: **15 Years**

(21) Appl. No.: **29/937,653**

(22) Filed: **Apr. 16, 2024**

(30) **Foreign Application Priority Data**

Oct. 18, 2023 (JP) ..... 2023-021590 D

(51) **LOC (15) Cl.** **10-04**

(52) **U.S. Cl.**

USPC **D10/46**

(58) **Field of Classification Search**

USPC D10/75, 103, 70, 78, 46, 74, 81, 96, 99,
D10/100, 102, 61, 65

CPC G01N 33/004; G01N 33/2025; G01N

(57) **CLAIM**

The ornamental design for a sensor as shown and described.

DESCRIPTION

FIG. 1 is a front perspective view of a sensor showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is a reference view of the usage state thereof.

The broken lines depict portions of the sensor that form no part of the claimed design.

1 Claim, 7 Drawing Sheets
